Primary Examiner — Eric Goodman*Assistant Examiner* — Ryan Harvey(74) *Attorney, Agent, or Firm* — Keusey & Associates, P.C.(57) **CLAIM**

The ornamental design for a brush with triangular ferrule, as shown and described.

DESCRIPTION

FIG. 1 is a top, front, right side perspective view of my new design of a brush with triangular ferrule.

FIG. 2 is a back side elevational view thereof.

FIG. 3 is a cross-sectional view of the ferrule taken along the line III-III from FIG. 2.

FIG. 4 is a cross-sectional view of the ferrule taken along the line IV-IV from FIG. 2.

FIG. 5 is a cross-sectional view of the ferrule taken along the line V-V from FIG. 2.

FIG. 6 is a front side elevational view thereof.

FIG. 7 is a right side elevational view thereof.

FIG. 8 is a left side elevational view thereof.

FIG. 9 is a top plan view thereof; and,

FIG. 10 is a bottom plan view thereof.

The broken lines showing a handle are included to show environmental structure and form no part of the claimed design.
